Primary Examiner — Elizabeth A Albert*Assistant Examiner* — Karen E Eldridge Powers(74) *Attorney, Agent, or Firm* — Macleod Dixon LLP**(57) CLAIM**

I claim the ornamental design for a cap, as shown and described.

DESCRIPTION

FIG. 1 is a perspective view of the cap.

FIG. 2 is a front view of the cap.

FIG. 3 is a left side view of the cap, the right side being a mirror image thereof.

FIG. 4 is a back view of the cap.

FIG. 5 is a top view of the cap; and,

FIG. 6 is a bottom view of the cap.

The broken lines shown in the drawings are stitch lines and form a part of the claimed design.
